Attorney

UNITED STATES PATENT OFFICE.

DANIEL E. McIVER, OF DULUTH, MINNESOTA, ASSIGNOR OF ONE-THIRD TO JOHN S. McIVER AND ONE-THIRD TO A. SELMER OLSON, BOTH OF DULUTH, MINNESOTA.

SIGNALING DEVICE.

Application filed September 12, 1925. Serial No. 56,064.

To all whom it may concern:

Be it known that I, DANIEL E. McIVER, a citizen of the United States, residing at Duluth, in the county of St. Louis and State of Minnesota, have invented certain new and useful Improvements in Signaling Devices, of which the following is a specification, reference being had therein to the accompanying drawing.

10 This invention relates to signaling devices and has special reference to such particularly adapted for use on an automobile to prevent theft of same.

15 The principal object of my present invention is to provide a practical and safe housing for such a device.

Other objects and advantages will appear in the further description of the invention.

20 Referring now to the accompanying drawing, forming part of this application and in which like reference characters indicate like parts:

25 Figure 1 is an elevation partly in section of an installation of the device embodying my invention; and

Figure 2 is a top plan view of the whistle housing illustrated in open position.

I am aware that somewhat similar devices have been employed, that is to say an alarm whistle associated with the engine of an automobile and controlled from the instrument board thereof, so that this idea broadly does not constitute my present invention.

30 1 represents the manifold of an automobile and 2 the instrument or dash board of same. 3 is a whistle of any well known type having an axial stem 4 therein controlling the intake valve 5 in the bottom of the whistle and 6 represents a bell-crank pivotally mounted upon the upper end of the whistle for controlling the stem 4. To the upper end of this bell-crank is attached the rod 7 which is mounted within the pipe or tube 8 leading from the spherical housing

40 9 about the whistle to the instrument board 2. The rod 7, which projects through the instrument board 2, is provided with an an-

nular notch 18 adjacent the extreme inner end thereof, and which notch when the rod is pressed inwardly so that the whistle is in 50 open position will be engaged by a suitable bolt 19 controlled by the lock 10 so that on the departure of the legitimate operator of the car the rod 7 may be pushed inwardly opening the whistle 3 and there locked by 55 the bolt 19, the operator carrying the key which controls same with him, so that in the event of an unauthorized operator attempting to move the car by the operation of the engine, the whistle will sound the desired alarm; such an arrangement however being old in the art, and further details of construction being unnecessary.

55 My present invention resides particularly in the spherical housing 9 made of two semi-spherical parts hinged as at 11 and each carrying half of an axially disposed externally threaded nipple 12 about which when the housing is closed the tube 8 is screw-threadedly mounted as clearly shown in Figure 1, 70 so that, as long as the assemblage is intact it becomes absolutely impossible to obtain access to the whistle and in any way tamper with same. The spherical housing 9 is provided with suitable perforations so that the 75 sound of the whistle is freely emitted therefrom.

75 An expansive helical spring 13 is shown as installed intermediate of the shoulder 14 on the rod 7 and the end of the nipple 12 to normally hold the rod outboard and the whistle closed.

80 Having thus described my invention, what I claim and desire to secure by Letters Patent, is:

85 A housing for a signaling device for automobiles comprising two hingedly united semi-spherical members, having a cooperative screw-threaded tube engaging nipple extending therefrom.

90 In testimony whereof I hereunto affix my signature.

DANIEL E. McIVER
